F. A. Cmejla
INVENTOR.

BY
Vetor J Evans
ATTORNEY.

UNITED STATES PATENT OFFICE.

FERDINAND A. CMEJLA, OF MILWAUKEE, WISCONSIN.

CURTAIN STRETCHER.

Application filed May 19, 1922. Serial No. 562,200.

To all whom it may concern:

Be it known that I, FERDINAND A. CMEJLA, a citizen of the United States, residing at Milwaukee, in the county of Milwaukee and 5 State of Wisconsin, have invented new and useful Improvements in Curtain Stretchers, of which the following is a specification.

This invention relates to a curtain stretcher and more particularly to a curtain stretcher clip and has for its primary object the 10 construction of a clip that will more effectively grip a curtain in such a manner that the curtain will not be torn.

An object of the invention is to provide 15 an inexpensive clip that will engage the curtain in a flat manner so as to prevent the clip from passing through the curtain and thereby tend to break the mesh.

A feature of my invention is the novel 20 manner of constructing the limbs of the clip and mounting thereon a particularly shaped slide so that the limbs will be effectively locked in clamping position and besides the slide readily move off of the limbs.

25 With these and other objects in view the invention will be better understood from the following detailed description taken in connection with the accompanying drawing wherein:

30 Fig. 1 is a fragmentary portion of a curtain stretcher showing my clip applied thereto.

Fig. 2 is a side elevation of the clip when open.

35 Fig. 3 is a side elevation of the clip when clamping a curtain.

Fig. 4 is an end elevation of the clip showing the position of the extremities when the slide is being removed or put on the limbs.

40 Fig. 5 is an enlarged detail view of a portion of the limbs.

Again referring to the drawing illustrating one of the many constructions of my invention the numerals 1 and 2 designate a 45 pair of rods having adjustable connection with each other as indicated at 3. My improved clips 4 are loosely mounted on the rods and may be adjusted thereon or removed without disconnecting the rods or destroying their adjusted relation. Each clip is made from a single length of material, for the sake of cheapness a single length of

wire, that is bent to form an open ring 5 is mounted on the rod. Diverging arms 6 and 7 are formed as continuations of the ring 55 and their extremities 8 and 9 are given L-shaped formations and the extreme ends of the limbs are flattened as indicated at 10 so as to move in flat engagement with each other and into engagement with the curtain 60 11 when interposed therebetween. The diameter of the material from which the clip is made is great enough to prevent the ends from passing through the mesh of the curtain and thus it will be seen that the curtain 65 is effectively gripped between the flattened surfaces and in such a manner that the same will not be subject to a tearing action.

For the purpose of holding the limbs in clamping position I provide the slide 12 70 which is stamped from sheet metal and has a diamond shaped opening 13, the walls 14 of which incline towards the circular recesses 15.

In the sliding of the slide on the limbs the 75 cam action will effectively force the limbs into the recesses so that the slide may have the best binding action on the limbs.

It will be noted in Fig. 4 the extremities may be readily snapped passed one another 80 by bending the limbs laterally to allow the slide to be quickly placed thereon or removed therefrom but owing to the particular arrangement of the recesses and their action with the limbs the ends will always 85 move into flat engagement unless the limbs are subject to a lateral strain by pressure of the fingers.

It is, of course, to be understood that the invention may be constructed in various 90 other manners and the parts associated in different relations and, therefore, I do not desire to be limited in any manner except as set forth in the claims hereunto appended.

Having thus described my invention what 95 I claim is:

1. A curtain stretcher clip consisting of a single length of wire bent to form a ring, diverging limbs extending from the ring, each limb having its extremity bent into L- 100 shaped formation with the extreme end flattened, a slide having an opening, curved recesses communicating with the opening, said opening adapted to receive therein the limbs

and having inclined converging walls coacting with the limbs to move the same into said recesses.

2. A curtain stretcher clip having its ends flattened and adapted to move into flat end engagement with each other, a slide for clamping the ends in engagement with each other, said slide having a diamond shaped

opening, and further provided with curved recesses in the ends of the openings whereby the inclined converging walls of the opening will guide the arms of the clip into the recesses.

In testimony whereof I affix my signature.

FERDINAND A. CMEJLA.
